UNITED STATES PATENT OFFICE.

LOUIS MANNSTAEDT, OF KALK, GERMANY.

DESIGN FOR A SIDE GUIDE-RAIL.

SPECIFICATION forming part of Design No. 24,894, dated November 12, 1895.

Application filed August 15, 1894. Serial No. 520,432. Term of patent 7 years. Patented in Germany May 18, 1893, No. 14,443.

To all whom it may concern:

Be it known that I, LOUIS MANNSTAEDT, partner of the firm of Façonsisen-Walxwerk L. Mannstaedt & Co., residing at Kalk, near Cologne, in the Province of Rhenish-Prussia, Germany, have invented and produced a new and original Design for Side Guide-Rails for Roller Window-Shutters, (patented in Germany May 8, 1893, No. 14,443,) of which the following is a specification, reference being had to the accompanying drawings, showing a part thereof.

Figure 1 in the accompanying drawings is a cross-section through the guide-rail for

roller window-shutters. Fig. 2 is a perspective view of the same.

The leading feature of my design for guide-rails for roller window-shutters consists in the U-shaped rail having the outer high ribs *a a* and the inner raised ribs *B B* and the deep channel *C* between them.

What I claim is—

The design for a side guide rail herein shown and described.

LOUIS MANNSTAEDT.
